H. E. CAMPBELL,
WINDOW FRAME AND SASHES,
APPLICATION FILED APR. 1, 1918.

Patented July 23, 1918.

Fig. 5.

Inventor
Harry E. Campbell
By, his Attorney
Sam Benjamin

UNITED STATES PATENT OFFICE.

HARRY E. CAMPBELL, OF NEW YORK, N. Y.

WINDOW FRAME AND SASHES.

1,273,453.

Specification of Letters Patent. Patented July 23, 1918.

Application filed April 1, 1918. Serial No. 225,915.

To all whom it may concern:

Be it known that I, HARRY E. CAMPBELL, a citizen of the United States, residing at New York, in the county of New York and State of New York, have invented a certain new and useful Improvement in Window Frames and Sashes, of which the following is a specification.

In U. S. Letters Patent No. 1,241,090, dated Sept. 25, 1917, and in other Letters Patent hitherto granted to me, I have set forth a window frame and sash construction wherein the hollow jambs and the sash frames are all of sheet metal, and wherein the sliding sashes have laterally extending plates on their vertical members entering slots in the inner walls of the jambs. This construction having entered into very extensive use, I have been led to study the problem of constructing wooden sashes and jambs with the object not only of securing to this type of structure certain advantages incident to the wholly metal construction, but the overcoming of difficulties which are peculiar to the wooden construction; and, in addition, of producing a simple structure easily and cheaply made by the house carpenter or builder.

In the accompanying drawings—

Figure 1 is a horizontal section through the ends of the sashes and one of the hollow jambs. Fig. 2 is a similar section, with portions of the jamb walls broken away. In Fig. 1 the laterally extending plates Q, R are shown secured to the front sides of the sashes, and in Fig. 2 said plates are shown secured to the rear sides. Fig. 3 is a section similar to Fig. 1, showing the wooden members incased in thin sheet metal for fire protection purposes, such protected wood being commonly known in the market as "kalamien". Fig. 4 is a vertical section on the line 4, 4 of Fig. 2, showing portions of the sashes in elevation, and a portion of the inner wall of one of the jambs in section. Fig. 5 is a sectional view of the inner portion of one of the plates Q or R, showing

a manner of making the edge of the plate adjustable with respect to the face of bar I.

Similar letters of reference indicate like parts.

A and B are sliding sashes, provided with any suitable counterbalancing means, not shown. The sash frames are of wood, and the glass panes C are seated in said frames and secured by strips D in any suitable way. The two jambs respectively on opposite sides of the sashes are alike, so that a description of one jamb applies to both. Said jambs are hollow, and their walls are of wood. One of the jambs is shown at E, and comprises the following parts: a rear wall F, and outer side wall G, a front wall H, and an inner side wall formed as hereinafter described. The outer side wall G is secured to the rear wall F and to the front wall H. Seated at one edge in a mortise in rear wall F is a wooden bar I which projects into the space within the jamb and is parallel to wall G. Secured to the face of bar I is a transverse partition J, with the face of which the edge of the side rail of sash B is in sliding contact. The inner jamb wall has an outer member K secured to front wall H, and an inner member L secured to rear wall F and preferably meeting bar I. The free edge of member K is beveled and preferably rounded, as shown at M. On the inner member L is a projection, similarly beveled and rounded, as shown at N. The partition J is flared at its free edge and beveled as shown at O and P.

In Fig. 1 the sash B is in sliding contact with the face of partition J, and the sash A in similar contact with member L and the edge of rear wall F. In Fig. 2 the sash B is in contact with member K of the jamb wall, and the sash A is in similar contact with the face of partition J.

Between the rounded and beveled edges M and O and between the rounded and beveled edges N and P are gaps or vertical slots, which extend from top to bottom of the jamb. Secured to each sash are laterally

extending plates Q, R of metal. The plate Q is attached to sash B, passes through the slot between edges M, O, and at its free end is preferably in sliding contact with the 5 face of bar I. The plate R is attached to sash A, passes through the slot between edges N, P, and at its free end is preferably in sliding contact also with the face of bar I. In Fig. 1 the plates Q, R are secured to the 10 front side, and in Fig. 2 to the rear side of the respective sashes. Either arrangement may be adopted, as the maker may desire. In Fig. 3 the arrangement of plates shown in Fig. 1 is represented. The wooden members shown in Fig. 3 are each covered with 15 thin sheet metal for purposes of fire protection. Such covering is no part of my present invention, my object being simply to show that such covered members may be 20 used, if desired, in the construction previously described.

It will be obvious from the foregoing that all of the structural members of the sash frames and jambs are of wood, the laterally 25 extending plates Q, R only being of metal. As these plates are simply flat strips, preferably equaling in length the sash side rails to which they are affixed, they can easily be 30 attached by screws, for example, as shown at S, by any carpenter. Said plates are, of course, on both sides of each sash.

Each plate is a barrier to the entrance of moisture or drafts of air through the joint between sash and frame. The partition J 35 is still another barrier. It is practically impossible for either moisture or air currents to pass over the front side of plate Q, through the joint between the edge of that plate and bar I, then along the rear side of 40 said plate and the joint between the sash and partition J, and then travel around the plate R in the same way, and still get into the building. Wooden sashes and frames are, as well known, difficult to keep weather- 45 tight, and the usual, and even necessary, expedient is the application of weather-strips. In my construction no weather-strips are required at all. The sashes run 50 up and down with ease. If it be desired to keep the free edges of the plates Q, R in sliding contact with the face of bar I, I may make such contact adjustable by forming 55 each plate in two parts U, V, as shown in Fig. 5, the part U having the contact edge being slotted to receive a clamping bolt W, so that said edge may be adjusted with 60 reference to bar I. In this way, I can allow for any possible expansion or shrinkage of the wooden parts which might cause either 65 too close or too loose a fit of said plate edge against the bar face. The elimination of weather-strips in wooden construction is of especial importance. In fact I find it costs less to produce my present construction than

to produce the cheapest sort of wooden sash 65 and frame, with the cost of the least expensive of weather-strips now in the market added.

I claim:

1. A window-frame and sash construction, 70 comprising a hollow jamb of wood having in its inner wall a vertical slot, a sash of wood having a side rail in sliding contact with said wall, and on said rail a laterally extending plate of metal entering said jamb 75 through said slot.

2. A window-frame and sash construction, as in claim 1, further including a fixed bar 80 of wood projecting into said jamb, the said laterally extending plate having its free vertical edge in sliding contact with said bar.

3. A window-frame and sash construction, as in claim 2, the said plate being formed in two parts adjustably connected, one of 85 said parts having a free vertical edge in proximity to a face of said bar and adjustable with respect to said face.

4. A window-frame and sash construction, comprising a hollow jamb of wood having 90 in its inner wall a vertical slot, a sash of wood having a side rail in sliding contact with said wall, a fixed bar of wood projecting into said jamb, and on said sash rail a laterally extending plate of metal entering 95 said jamb through said slot and having its free vertical edge in sliding contact with a face of said bar.

5. A window-frame and sash construction, as in claim 1, the edges of the said wall 100 bounding said slot being beveled to produce narrow bearing surfaces for said laterally extending plate.

6. A window-frame and sash construction, comprising a hollow jamb of wood having 105 a vertical opening in its inner wall, a fixed bar of wood secured to and projecting into said jamb, a wooden partition secured to the face of said first-named bar and projecting into said wall opening, there being gaps between said partition bar and the edges of 110 said wall opening, two wooden sash frames having their corresponding side rails in sliding contact with said inner wall, and on each side rail a laterally projecting plate of metal, the said plates respectively entering 115 said jamb through said gaps.

7. A window-frame and sash construction, comprising a hollow jamb of wood having a vertical opening in its inner wall, a fixed bar of wood secured to and projecting 120 into said jamb, a wooden partition secured to the face of said first-named bar and projecting into said wall opening, there being gaps between said partition bar and the edges of said wall opening, two wooden sash frames having their corresponding side rails in sliding contact with said inner wall, and on each side rail a laterally projecting plate 125

of metal, the said plates respectively entering said jamb through said gaps and having their free edges in sliding contact with a face of said bar.

5 8. A window-frame and sash construction, as in claim 4, the edges of said inner wall bounding said opening being beveled, and the said partition bar being formed with correspondingly beveled edges to produce at

said gaps narrow bearing surfaces for said 10 laterally extending plates.

In testimony whereof I have affixed my signature in presence of two witnesses.

HARRY E. CAMPBELL.
